UNITED STATES PATENT OFFICE

106,327

DESIGN FOR A TOOTHPICK HOLDER

Karl Schulz, Chicago, Ill.

Application August 16, 1937, Serial No. 71,135

Term of patent 3½ years

To all whom it may concern:

Be it known that I, Karl Schulz, a citizen of the United States, residing at Chicago, in the county of Cook and State of Illinois, have invented a new, original, and ornamental Design for a Toothpick Holder, of which the following is a specification, reference being had to the accompanying drawing, forming a part thereof.

Fig. 1 is a top plan view, slightly in perspective, of the toothpick holder, showing my design; and Fig. 2 is a front elevational view thereof, also slightly in perspective.

I claim:

The ornamental design for a toothpick holder, as shown.

KARL SCHULZ.
